UNITED STATES PATENT OFFICE.

WILLIAM J. BULLOCK, OF HARTFORD, CONNECTICUT, ASSIGNOR OF TWO-THIRDS TO FREDERICK C. ROCKWELL AND FRANK S. FRENCH, OF SAME PLACE.

AIR-VALVE.

SPECIFICATION forming part of Letters Patent No. 611,211, dated September 20, 1898.

Application filed October 7, 1897. Serial No. 654,373. (No model.)

To all whom it may concern.

Be it known that I, WILLIAM J. BULLOCK, a citizen of the United States, residing at Hartford, in the county of Hartford and State 5 of Connecticut, have invented certain new and useful Improvements in Air-Valves, of which the following is a specification.

The invention relates to the class of valves that are more particularly designed and intended for use with pneumatic tires, but that are adapted for other articles which are inflated with air.

The object of the invention is to provide a valve of this nature which will be light in weight, simple in construction, and inexpensive to manufacture and which may be closed and tightly locked before the air-pump which is used to inflate the article to which the valve is attached is disconnected.

20 The embodiment of the invention shown in the accompanying drawings has a tube by means of which the valve is attached to the article to be inflated, a valve-disk for closing the opening and preventing the escape of air 25 outwardly through the tube, a sleeve provided with means for the connection of the air-pump mounted on the tube and arranged to lock and unlock the valve-disk, and a cap for protecting and sealing the opening through the 30 sleeve and for holding the sleeve against accidental movement.

Figure 1 of the drawings shows a side view of an air-valve that embodies the invention with the parts in the relative positions occupied when the valve is closed and locked. Fig. 2 shows a central longitudinal section of the valve with the parts in the same positions. Fig. 3 shows a side view, with the cap removed, of the tube and sleeve in the positions 40 occupied when the valve is open. Fig. 4 shows a central longitudinal section of the parts shown in Fig. 3. Fig. 5 shows a sectional view of the valve with a cap of modified construction, and Fig. 6 shows a similar 45 view with a different form of cap.

In the views, 1 indicates the tube that is adapted to be attached to the article to be inflated. The outer end of this tube is provided with a screw-thread, preferably a left-hand 50 thread. The opening 2 through the outer end

of the tube is reduced in diameter, and on the shoulder inside which results by thus reducing the opening is the valve-disk seat.

Mounted on the threaded end of the tube is a sleeve 3, the interior thread of this sleeve 55 being left-handed if the thread on the end of the tube is left-handed. The outer end of this sleeve is provided with an interior thread for the attachment of the pump connection.

The valve-disk 4, that is in the tube and is 60 adapted to open from and close against the seat, is secured to a stem 5, which extends through the reduced opening in the outer end of the tube into the sleeve. The disk-stem is preferably provided with a head 6, that is 65 arranged to be engaged by a flange 7 on the inside of the sleeve. When the sleeve is rotated so as to move off from the end of the tube, the flange engages the head of the stem and draws the valve-disk against the seat in 70 the tube. This locks the valve-disk in its closed position and if the threads are left-handed is accomplished by turning the sleeve toward the right. If the threads on the end 75 of the tube and in the sleeve are right-handed instead of left, the same result is accomplished by turning the sleeve toward the left. When the sleeve is so rotated as to move onto the end of the tube, the flange moves away from the head of the stem, so that the valve-disk 80 may be moved from its seat. The sleeve is preferably knurled or roughened on its exterior, so that it may be grasped for turning.

If there is pressure in the inflated article to which the tube is attached and which is to 85 be further inflated, the valve-disk is normally held closed by that pressure and can only be opened by greater pressure applied from without. With the cap removed and the parts in the positions shown in Figs. 3 90 and 4 a pump can be connected with the sleeve and by its means air forced past the valve-disk. When the pressure in the interior is sufficiently raised before the pump is disconnected, the sleeve can be rotated, so 95 as to lock the disk against its seat. With the valve-disk locked in this manner the pump is disconnected and a cap is screwed on to close the end of the sleeve. The cap 8 may be provided with an interior thread and 100

the sleeve with a corresponding exterior thread. These are preferably right-hand threads, and when the sleeve is in the position illustrated in Fig. 2 the cap can be 5 screwed on until its edge engages a packing-washer 9, placed about the tube on a collar 10. If the threads between the end of the tube and the sleeve are left-handed and the threads between the sleeve and the cap are 10 right-handed, the turning on of the cap tends to rotate the sleeve in a direction that moves it off from the end of the tube and causes it to tighten the valve-disk against its seat. When the edge of the cap engages the packing-washer 9, the opening into 15 the sleeve is protected and a tight joint is made in a manner that renders it impossible for the interior sleeve to rotate and loosen the valve-disk from its seat without first 20 removing the cap. When the cap is turned to be removed, the tendency of the rotation is to first move the sleeve from the position shown in Fig. 2 to the position shown in Fig. 4, and then when the sleeve engages with the 25 washer 9 further rotation of the sleeve is stopped, so that the cap readily unscrews from the sleeve. This results when the tube and sleeve threads are left-handed and the cap and sleeve threads are right-handed and 30 when the tube and sleeve threads are loose, so that there will be less friction between the smaller engaging tube and sleeve threads than between the larger engaging sleeve and cap threads. With this construction the 35 valve-disk is held closed by the air-pressure in the inflated article and then is tightly locked in that position by turning the sleeve, which may be accomplished before or after the pump is disconnected. When the cap is 40 turned on, the tendency is to turn still further the locking-sleeve, for the cap when screwed on is turned in the same direction as the sleeve is turned to lock the valve-disk. Thus the turning on of the cap insures the 45 tight locking of the valve-disk and also the sealing of the joint between the tube and the cap. With the cap in place there are two joints sealed and locked in such manner that the escape of air from the inflated article 50 through the valve is practically impossible.

If desired, the collar 10 may be provided with a thread and the thread in the cap may be arranged to screw upon the threaded collar, as illustrated in Fig. 5, or the cap may 55 be formed so as to screw into the interior thread in the outer end of the sleeve provided for the attachment of the pump connection, as illustrated in Fig. 6. In both of these constructions the exterior wall of the 60 sleeve may be left smooth or ornamented, as desired.

A valve which embodies this invention is not liable to become disarranged or wear out, and the few parts of which it is composed are 65 cheap to manufacture and easy to assemble. The valve-disk is locked closed positively and can be thus locked before the pump is

disconnected or afterward, as desired. After the pump is disconnected and the valve-disk is locked the locking is made certain 70 and the sealing is repeated, so that this valve when the cap is in position is doubly locked and doubly sealed. The parts may be so arranged that the valve-disk is unlocked by the act of removing the cap, or they may be arranged so that the valve-disk need not be unlocked until after the pump is connected. 75

I claim as my invention—

1. An air-valve having a tube with a reduced opening through one end, a sleeve arranged to move onto and off from the end of the tube that has the reduced opening, a valve-disk located within the tube and having a stem adapted to be engaged by a part of the sleeve when the sleeve is moved off from the 80 end of the tube and held so as to lock the valve-disk closed, and a cap turning on the sleeve and arranged to lock and unlock the sleeve, substantially as specified.

2. An air-valve having a tube with a reduced opening through one end, a sleeve arranged to move onto and off from the end of the tube that has the reduced opening, a valve-disk located within the tube and having a stem adapted to be engaged by a part of the 85 sleeve when the sleeve is moved off from the end of the tube and held so as to lock the valve-disk closed, and a threaded cap arranged to be screwed onto the tube so as to seal the opening through the sleeve, substantially as specified.

3. An air-valve having a tube with a reduced opening through one end and an exterior thread around that end, a sleeve with an interior thread engaging the exterior 90 thread on the end of the tube, a valve-disk located within the tube and having a stem adapted to be engaged by a part of the sleeve when the sleeve is turned so as to move off from the end of the tube and held so as to 95 lock the valve-disk closed, and a cap turning onto and off from the sleeve and arranged to lock and unlock the sleeve, also the valve-disk, substantially as specified.

4. An air-valve having a tube with a reduced opening through one end and an exterior thread around that end, a sleeve with an interior thread engaging the exterior 100 thread on the open end of the tube, a valve-disk located within the tube and having a 105 stem adapted to be engaged by a part of the sleeve when the sleeve is turned so as to move off from the end of the tube and held so as to lock the valve-disk closed, and a threaded cap arranged to be screwed into position to seal 110 the opening through the sleeve, substantially as specified.

5. An air-valve having a tube with a reduced opening through one end, a sleeve arranged to move onto and off from the end of the tube that has the reduced opening, a valve-disk located within the tube and having a stem adapted to be engaged by a part of the 115 sleeve when the sleeve is moved off from the 120 end of the tube and held so as to lock the valve-disk closed, and a threaded cap arranged to be screwed into position to seal 125 the opening through the sleeve, substantially as specified.

end of the tube and held so as to lock the valve-disk closed, and a cap having a thread arranged to engage a thread on the sleeve, said cap when turned so as to move toward 5 the tube, sealing the opening through the sleeve and by engagement with a part of the tube locking the sleeve against movement, substantially as specified.

6. An air-valve having a tube with a reduced opening through one end, a sleeve with threads engaging threads on the end of the tube, a valve-disk located within the tube and arranged to be locked in a closed position by the rotation of the sleeve, and a cap having 10 threads engaging threads on the sleeve in such manner that the turning on of the cap

tends to cause the sleeve to more tightly hold the valve-disk locked closed and the turning off of the cap tends to move the sleeve so as to unlock the valve-disk, substantially as 15 specified.

7. An air-valve having a tube, a valve-disk within the tube, a sleeve turning on the end of the tube and arranged to lock and unlock the valve-disk, and a cap turning on the sleeve 20 and arranged to lock and unlock the sleeve, substantially as specified.
